(57) **CLAIM**

The ornamental design for a pencil sharpener, as shown and described.

DESCRIPTION

FIG. 1 is a front perspective view of a pencil sharpener;

FIG. 2 is a side perspective view thereof;

FIG. 3 is a rear perspective view thereof;

FIG. 4 is an opposite side perspective view thereof;

FIG. 5 is a front elevation view thereof;

FIG. 6 is a side elevation view thereof;

FIG. 7 is an opposite side elevation view thereof;

FIG. 8 is a rear elevation view thereof;

FIG. 9 is a top plan view thereof; and,

FIG. 10 is a bottom plan view thereof.

The broken lines showing features and the surface in FIG. 10 are included for the purpose of illustrating a portion of the bottom that forms no part of the claimed design.
